STRAIGHT HOLE BIT

James D. Hughes, Houston, Tex., assignor to Oil Well Engineering Company, Houston, Tex., a corporation of Texas

Application April 22, 1938, Serial No. 203,472

5 Claims. (Cl. 255—61)

The invention relates to a bit used in the rotary method of drilling wells and particularly to a bit which is adapted to drill a straight hole.

In the rotary method of drilling wells the bit is attached to the lower end of a drill stem and penetrates the formation by rotary motion usually in a clockwise direction. A portion of the weight of the string of drill pipe is allowed to rest upon the drill bit to force it into the formation, and of course, flushing fluid is circulated through the drill stem and the bit to wash the cuttings away from the cutter blades.

In view of the fact that the bit rotates constantly in one direction it usually has a tendency to form the well bore in a spiral as it moves downwardly into the formation. In other instances the bit may engage a fissure in a rocky formation or boulders or other more or less rigid obstructions in the softer formations which tend to deflect the well bore from a substantially vertical path.

Various types of equipment have been provided for correcting the deflection of the well bore, such as whipstocks which have an inclined face to change the inclination of the bore, and other types of equipment. The present invention directs itself to a particular type of bit wherein a plurality of cutter blades are provided in such a construction and arrangement that a greater unit area pressure will be created against one portion of the side wall of the well bore, so that there is a tendency to direct the well bore along a curve in the direction of the side wall against which the greater pressure is exerted.

It is one of the objects of the invention to provide a drill bit having one blade which extends radially a greater distance than the remaining blades.

Another object of the invention is to provide a drill bit which will cause the drill stem to move eccentrically in the well bore.

Still another object of the invention is to provide a method of correcting the inclination of the well bores by applying the transverse component of force caused by raising a portion of the drill stem away from the low side of the well bore against the side wall on the low side, so as to cut away the side wall and gradually curve the well bore from its inclination into a vertical direction.

Another object of the invention is to provide a method of drilling straight holes by cutting away the side wall on the low side of the well bore.

Still another object of the invention is to provide a three-way drag bit one blade of which

carries a plurality of outstanding cutter teeth on the side wall, which teeth project a greater distance than the side wall of the remaining blades.

Still another object of the invention is to provide a drill bit which will maintain a straight hole by correcting the inclination automatically due to the construction of the bit used.

Other and further objects of the invention will be readily apparent when the following description is considered in connection with the accompanying drawing wherein:

Fig. 1 is a side elevation of a drill bit embodying the invention.

Fig. 2 is a bottom plan view of the bit of Fig. 1.

Fig. 3 is a transverse sectional view taken on the line 3—3 of Fig. 1; and looking downward.

Fig. 4 is a diagrammatic view showing the general arrangement of the method of correcting the inclination of a well bore and showing the bit in position and applying the excess pressure against the low side of the hole.

The bit which may be used in practicing the invention is illustrated at 2 in Fig. 1 and includes a body portion 3 having a shank 4, which is threaded for connection to a drill sub or collar 5, which is best seen in Fig. 4. The drill stem 6 is connected to the drill collar 5 and extends to the surface. Flushing liquid may be circulated through the passage 7 in the drill stem and is arranged to discharge from the ports 8 in the bottom of the body 3. A chamber 10 in the body 3 feeds the flushing fluid to all three of the openings 8, the arrangement of which are best seen in Figs. 2 and 3. These ports 8 are directed downwardly and outwardly, as seen in Fig. 1, so that the discharge therefrom is directed in such a manner that it will carry the cuttings away from the lower cutting edges 11 of the blades and also directs the flow of liquid outwardly so that it will wash the side wall of the well bore as it passes upwardly around the bit.

As seen in Fig. 2 the body 3 has, in the form illustrated, three blades 14, 15 and 16, which are symmetrically arranged to extend radially from the body. A discharge port 8 is directly in front of each of the blades. In addition to the lower cutting edge 11 on each blade there is a side wall cutter or reamer portion 17 on the blades 14 and 15, which two blades are identical in their construction.

The third blade 16 is of particular or peculiar construction, first, because it extends inwardly to a point 18 across the center of the body. In this manner this heel portion 18 of the blade 16

will cut away the central portion of the formation being penetrated.

The blade 16 has another peculiarity in that it extends radially a greater distance from the body than do the blades 14 and 15. This is apparent from both Figs. 2 and 3. The side wall 20 of the blade 16 is formed with a plurality of teeth or lugs 21, which are spaced apart by the recesses or notches 22. The lower notch 23 of the group 10 may be of less depth than the remaining notches, if desired. The side walls 17 and 20 may be rearwardly inclined as seen in Figs. 2 and 3.

It is intended that hard surfacing material such as tungsten carbide or other suitable substances will be applied to the faces 11 and to the side wall portions 17 and 20 particularly upon the teeth 21.

In ordinary drilling operations the side walls 17 of the blades tend to ream the hole and maintain it of a proper gauge, which is the size of the bit, but with the present type of bit it is intended that the blade 16 will accomplish a greater reaming action on one side of the hole than it does on the other when the hole is inclined away 20 from the vertical and this excessive reaming action will occur on the side wall of the hole, which is on the low side.

This action will be accomplished by applying a greater unit area pressure against the side wall 30 due to the fact that this blade 16 projects radially from the body a greater distance than the other blades and due also to the fact that the teeth 21 are provided and the pressure against the side wall will in this manner be concentrated upon these teeth portions so that they will penetrate the side wall more than will the reaming edges on the other blades. This is particularly true when the well bore is inclined but when the well bore is vertical the action of 40 the blade 16 will be uniform in its reaming action all the way around the side wall.

For purposes of illustration a three-way bit has been shown but it is to be understood that any desired number of blades may be provided 45 so long as one blade is of the type of the blade 16. More than one blade may be constructed like the blade 16 if desired.

The operation of the method is best seen in Fig. 4 where the well bore 30 has been drilled 50 and for some reason or other has deviated from the vertical and is inclined. As shown the side wall 31 is on the low side of the hole whereas the side wall on the high side of the hole is indicated at 32. The drill bit 2 is shown as having 55 been connected to the drill collar 5 which may be of any desired length and is usually of a heavy rigid construction. In some instances such drill collars may be 50 to 90 feet in length and of a very thick gauge of material, so that the rigidity 60 thereof will tend to hold the bit against sharp deflections or inclinations away from the vertical. In the figure the drill collar has been shown as broken between its ends.

Above the drill collar 5 is a drill stem 6 and 65 by connecting successive lengths of drill stem to each other the bit 2 has been lowered into the well bore and in Fig. 4 is shown as having been seated upon the bottom 33 of the well bore 30. The bit has been illustrated in such a position 70 that the blade 16 is shown as pressing against the side wall 31 on the low side of the hole and it should be particularly noted that the collar 5 and the drill stem 6 are not centered in the well bore 30 but that they have been raised away 75 from the low side wall 31 to a position near the

side wall 32, and that this raising of the drill collar and drill stem away from the low side was caused by the blades 16 pressing against the side wall 31.

If the well bore is vertical there would be a 5 transverse or horizontal component of force but it would be uniform against the side wall throughout its circumference because rotation of the bit would cause the drill stem and drill collar to move eccentrically in the well bore, but the eccentricity 10 would be uniform and the blade 16 would accomplish a uniform reaming action throughout the circumference of the well bore. When, however, the well becomes inclined as seen in Fig. 4, it seems obvious that the reaming action will 15 be increased on the lower portion of the side wall, as at 31, due to the fact that the drill collar and drill stem are inclined from the vertical and every time the eccentric blade 16 comes around to the low side of the hole the reaming action will 20 be increased. This increase begins on a diameter perpendicular to the sheet of the drawing and increases gradually until it reaches a diameter in the plane of the sheet of drawing and then decreases again as it approaches the perpendicular diameter again. Of course, when the other blades 14 and 15 travel around on the low side 25 of the hole they permit the drill collar and drill stem to settle down toward the low side of the hole 31 and the pressure on the reaming edges 30 17 is reduced but every time the blade 16 comes around to the low side of the hole a greater unit area pressure to accomplish a reaming action occurs, first, because the drill stem and drill collar must be lifted away from the low side of 35 the hole if the resistance of the formation to cutting is sufficient.

If the formation is very soft, of course, the blade 16 will merely cut it away and the weight of the drill stem and drill collar will thence be utilized to accomplish a reaming action tending to correct the inclination of the hole. On the other hand, if the formation resists cutting the 40 resistance will be overcome by a force which is increased due to the fact that the drill collar and drill stem will have to be lifted somewhat and the transverse component of this force, due to the weight of the drill collar and drill stem, will be available to increase the force tending to cut away the low side of the hole.

As the bit is rotated the well bore will be reamed 45 away on the low side 31, as seen in Fig. 4, so that the path of the well bore will be curved so that the side wall 31 gradually approaches the vertical as at 35.

The provision of the lugs 21 and notches 22 facilitates the cutting action on the low side of the hole when the well bore is inclined.

One of the particular advantages of the present bit is the fact that the inclination of the well bore is corrected automatically, as seen in Fig. 4, but when the well bore approaches the vertical the transverse component tending to force the blade 16 against the low side of the hole is reduced, because the drill collar and drill stem reside in the well at a lesser inclination so that the rate of correction is decreased as the vertical is approached, and is increased when the inclination is the greatest.

When the well bore becomes vertical then the 70 reaming action becomes uniform all the way around the circumference of the well bore and the drilling of the bore continues in a vertical position. If for some reason the bit is again deflected the blade 16 immediately proceeds to 75

ream away the low side of the hole at a rate in proportion to the inclination which has occurred so that the bit automatically compensates for any inclination which may occur, and the driller 5 may proceed with his drilling operation at a uniform rate without withdrawing the drill stem, to survey the well bore hole, to introduce a whipstock, or other deflecting tool. The driller is assuming that his well bore will remain substantially vertical because the bit automatically compensates for any inclination which occurs and this compensation is directly in proportion to the amount of inclination. When the inclination 10 disappears and the well bore becomes vertical then the reaming action is uniform and no further correction will occur.

Broadly the invention contemplates a means and method of drilling well bores whereby the bore will be maintained in a vertical position 20 and any inclination which occurs will be automatically corrected only to the extent that the well bore again becomes vertical.

What is claimed is:

1. A drag bit of the character described for 25 correcting and maintaining the direction of a well bore, including a body and blades, transverse cutting edges in substantially the same horizontal plane on all of said blades, and a serrated cutting side wall on one of said blades, said last 30 blade extending radially farther than the other blades.

2. A straight hole bit including a body, blades 35 thereon, one of said blades extending radially a greater distance than the remaining blades to create a greater unit area pressure on the low side of the bore being drilled when the bit is inclined from the vertical so as to ream such low side of the bore and correct the inclination, and bottom cutting edges on all of said blades, which 40 edges are disposed in substantially the same

transverse plane so that said bit body moves eccentrically of the bore upon rotation thereof.

3. A straight hole bit including a body, blades thereon, one of said blades extending radially a greater distance than the remaining blades 5 whereby the bit body moves eccentrically in the bore and the weight of the bit will create a greater unit area pressure on the low side of the bore being drilled when the bit is inclined from the vertical so as to ream such low side of the 10 bore and correct the inclination, said extending blade having alternate notches and teeth on the side wall, and bottom cutting edges on all of said blades which edges are in substantially the same transverse plane so as to cut the bottom of the 15 more as the side teeth cut the low side wall of the bore.

4. A drag bit for correcting the inclination of and drilling straight bores comprising a body, a 20 plurality of radial blades on the body and projecting below the body, transverse bottom cutting edges on all the blades disposed at the same elevation so that all blades cut the bottom of the bore being drilled, one of said blades including a portion extending radially a greater distance than 25 the remaining blades to cut the lower side wall when the bore is inclined.

5. A drag bit for correcting the inclination of and drilling straight bores comprising a body, a 30 plurality of radial blades on the body and projecting below the body, transverse bottom cutting edges on all the blades disposed at the same elevation so that all blades cut the bottom of the bore being drilled, one of said blades including a portion extending radially a greater distance than 35 the remaining blades to cut the lower side wall when the bore is inclined, and an inner portion on the same blade extending across the longitudinal axis of the body.

JAMES D. HUGHES.
